UNITED STATES PATENT OFFICE.

MERRILL A. FURBUSH, OF PHILADELPHIA, PA., ASSIGNOR TO MERRILL A. FURBUSH AND CHAS. A. FURBUSH, BOTH OF SAME PLACE.

CONDENSING MECHANISM FOR CARDING-MACHINES.

SPECIFICATION forming part of Letters Patent No. 243,241, dated June 21, 1881.

Application filed March 31, 1881. (No model.)

To all whom it may concern:

Be it known that I, MERRILL A. FURBUSH, a citizen of the United States, residing in Philadelphia, Pennsylvania, have invented an Improvement in Condensing Mechanism for Carding-Machines, of which the following is a specification.

My invention consists of the combination, in a carding-machine, of a series of ordinary rotating and reciprocating rub-rolls with reciprocating and traversing aprons, the object of my invention being to obtain the superior condensing effect of the aprons and the drawing and stretching effect of the rolls, which effect cannot be produced by the aprons alone.

In the accompanying drawings, Figure 1 is a plan view, showing the rub rolls of a carding-machine combined with the aprons; and Fig. 2, a vertical section on the line 1 2.

20 A A', Fig. 1, represent portions of the fixed frame of a carding-machine; and B a reciprocating bar adapted to guides on or forming part of the frame, and carrying the bearings a for the journals b of the series of rub-rolls D, 25 D', D², E, and E', another reciprocating bar below the first carrying the bearings for the journals of another set of rub-rolls, G, G', G², F, and F', Fig. 2. The two bars are reciprocated in contrary directions by eccentrics H and I, as 30 described in the Letters Patent No. 166,601, granted to me August 10, 1875.

The shafts b of the rub-rolls pass through and are arranged to slide in and turn with a series of cog-wheels, the hubs of which are 35 adapted to a series of bearings, d, on the fixed frame A, the upper and lower set of rolls being geared together by the said wheels, so as to revolve in the direction of the arrows, Fig. 2.

An endless apron, K, of leather or other 40 suitable material, passes round the rollers E

E', and another endless apron, K', round the rollers F F'.

The slivers stripped from the stripper-cylinder of the carding-machine pass, in the direction of the arrow, first between the upper 45 and lower set of rub-rolls, and thence between the aprons which move in the direction of the arrows, while they are reciprocated in contrary directions simultaneously with the rub-rolls.

The rolling and condensing of the slivers 50 can be more thoroughly accomplished by the combined effect of the two aprons than by the rub-rolls; but the latter possess this advantage, that there can be a slight drawing or stretching of the slivers as they pass between 55 the rolls, it being the practice in many carding-engines to adopt such gearing that there will be a slight progressive increase in the speed of the rollers from the first to the last, so as to produce the desired drawing effect. 60

By combining a series of revolving and reciprocating rolls with the reciprocating and traversing aprons, I gain the advantages of both systems, while the combination presents the opportunity of drawing or stretching the 65 slivers as they leave the last rollers and before they are seized by the aprons.

I claim as my invention.

The combination, in a carding-machine, of 70 rotating and reciprocating rub-rolls with traversing and reciprocating aprons, substantially as described.

In testimony whereof I have signed my name to this specification in the presence of two subscribing witnesses.

MERRILL A. FURBUSH.
